UNITED STATES PATENT OFFICE.

WALTER HARRISON BIDDLE, OF EASTBOURNE, ENGLAND.

COMPENSATING DEVICE.

1,263,193.

Specification of Letters Patent. Patented Apr. 16, 1918.

Application filed January 31, 1916. Serial No. 75,434.

To all whom it may concern:

Be it known that I, WALTER HARRISON BIDDLE, a subject of the King of Great Britain, residing in Eastbourne, England, have 5 invented a certain new and useful Compensating Device, of which the following is a specification.

This invention relates to apparatus for automatically compensating the expansion 10 or contraction of wires, rods or the like arranged between two relatively fixed points. It is, for instance, applicable for compensating the expansion and contraction of railway signal wires or point rods due to variations of temperature, or for similarly compensating comparatively small variations of 15 length of wires, rods or other connecting means due to any cause.

It consists essentially in cutting or severing 20 the wire, rod or other connecting means and attaching each of the cut or severed ends to one of a pair of pivoted levers, one or both of which are weighted or otherwise adapted to move with the end or ends of the 25 connecting means as the latter expands and contracts, and in providing an automatically adjustable link or connecting device between the levers adapted to cause them to move together at any position should a force be exerted 30 upon the connecting means.

The invention will be described as applied to the operating wires of railway signals. When applied to such wires, the apparatus may be placed at any position in the length 35 of the wire, but is preferably placed more or less in the center of the wire, for the reason hereinafter referred to.

The accompanying drawings illustrate by way of example several methods of carrying 40 out the invention. Figure 1 is a view showing one method of carrying out the invention; Fig. 2 shows a modified arrangement; Fig. 3 is a detail of same; Figs. 4, 5 and 6 show further modifications.

45 Referring to Fig. 1 the apparatus comprises two levers A, which may be pivoted on the same, or as shown, on separate pivots B, and are provided with weights C so arranged that the levers have a tendency to move away from one another. The signal wire D is cut or severed at the place where the compensating apparatus is to be arranged, and the severed ends are attached to the extremities a of the two levers A in 55 such a way that as the levers are pulled

or moved outward by their weight, they exert a tension on the two lengths of wire and keep them taut. It will be seen that as the lengths of wire D expand as the temperature rises, the levers A under the action of their weights C will tend to open out from one another, whereas should the atmosphere become cooler and contraction take place, the levers will tend to be drawn by the contracting lengths of wire toward one another. 60 65

Arranged between the levers is an adjustable link or block E adapted, as the levers A open or close, to move into or out of the space between the levers, in such a manner that the link or block E, in whatever position it takes, makes contact with or almost makes contact with both levers, so that if a pull is exerted on one of the levers A, it first engages the link or block E and then the link or block engages the other lever A 70 75 and both levers, maintained in practically the same relations as when the pull began, are thus moved over under the influence of the pull. When the extra tension is released the signal wires return to normal position 80 in known manner, carrying with them the two levers still locked together, till as they actually arrive at normal position the levers and the links become free from one another again. 85

In the arrangement shown in Fig. 1, in which the levers are arranged vertically, the link or block E is slung from the end of an arm F pivoted upon the supporting frame X, said arm being raised or lowered, according to the movements of the levers A, by a link G operated by the movement of one of the levers A. The sides of the levers A and of the link or block E are so shaped that within reasonable limits, at every position of the levers A, the block E engages or almost engages both the levers. The sides of the levers A may be toothed or serrated and the edges of the link or block E may be similarly toothed or serrated to insure 95 the better grip between the two levers and the adjustable intermediate link or block. 100

The levers are preferably arranged more or less vertically as shown, but they may be arranged horizontally, or at any other angle, in which case a spring S may be attached to the connecting link or block E, to draw it inward between the levers as they open out from one another, as shown in Fig. 1. However, where the device is arranged 110

vertically, or substantially so, and the weight of the link block E is sufficient, the spring can be dispensed with.

In the arrangement shown in Fig. 2 the levers A' which in this case may consist of straight rods or bars are mounted as before on pivots B' and to the free extremities α' of one of the levers A' is attached one of the severed ends of the signal wire D. To the same lever is freely pivoted a link E' which is normally free to slide over or through a rest or guide H (see Fig. 3) arranged in or on the side of the other lever A'. The other severed end of the wire D is passed over a guide α^2 at the extremity of the lever A' through which the link E' slides and is attached to the free end of said link E'. The upper side of the link E' is provided with teeth e and the guide H is provided with a stop J adapted to engage into the teeth e of the link E'. Normally under the action of the weight C and the tension of the wire D the link E' would tend to engage the stop J but a spring plunger K is provided in the guide H, which is adapted to normally hold the link E' out of engagement with the stop. The pressure of the plunger K is greater than that which would normally tend to engage the link and the stop but less than that exerted when the signal is to be pulled off, so that in this case the pressure of the plunger K is overcome and the link E' is raised into engagement with the stop J and both levers A' are moved over together while maintained in the same relative positions as at the commencement of the pull. Otherwise the link E' is free to slide in the rest or guide H as the levers A' open or close according to variations of length of the wire D.

The arrangement shown in Fig. 4 is similar to that shown in Fig. 2 except that instead of a spring plunger K to hold the link E' normally out of engagement, with the stop J, a weight L is employed for this purpose.

A somewhat similar arrangement is shown in Fig. 5. A link E' pivoted to the lever A' is provided, as described with reference to Figs. 2 and 4, but the method of engaging the link is different. For this purpose the upper end α^2 of the second lever A² is mounted so as to be capable of pivoting on the main portion of the lever but is normally held in line therewith by a weight M which holds it against a suitable stop N. This weight M preferably takes the place of the weight C on the lever A' but may be in addition thereto if desired. From a lug O on the front of the pivoted part α^2 depends a chisel-edged rod P adapted, when the part α^2 is bent forward, to engage into the teeth of the link E' and prevent its movement in the guide H.

In operation it will be seen that under

normal conditions the levers A' and A² are free to open or close as the wire expands or contracts, as described with reference to the other figures, but when an extra pull is exerted on the end α^2 it will bend forward, the chisel-edge P will engage teeth e of the link E' and the levers will be moved over together while maintained in the same relative positions.

Any other means of adjustably connecting the lever, so that the levers are free to open or close with regard to one another, but will move together around their pivots when a pull is exerted in another direction on the wire, may be employed.

When the invention is applied to rods, instead of wires, it is not necessary to weight the levers, as it is not required that they should exert a tension on the rod.

The invention can also be applied to any other purpose in which it is necessary to take up or compensate for the expansion or contraction of any wire rod or the like between two relatively fixed points.

As stated above, the apparatus is preferably arranged at or near the center of the wire, so that the expansion or contraction is taken up more or less equally by the two levers. This is not, however, necessary as the apparatus can be arranged at any position in the wire. Where it is arranged at one or other end of the wire, one of the levers may under normal circumstances remain practically stationary, all the expansion or contraction being taken up by the other lever.

As shown in the drawings, the levers are shown with the two ends of the wire or rod overlapping, but it is obvious that a similar arrangement can be employed when the relations of the levers are reversed and the ends of the wire or the like do not overlap. Such an arrangement is shown in Fig. 6 which illustrates a construction somewhat similar to that shown in Fig. 1, the essential difference being that, instead of a link block E arranged between the levers A, a link E² is employed which embraces the levers A² and is adapted to engage them on their outer sides when one of the levers is pulled. The link E² is raised or lowered to maintain it in almost engaging position with the levers A², at any position thereof, in the manner as is shown in Fig. 1.

Having thus described the said invention and the best means I know of carrying the same into practical effect, I claim:

1. Apparatus for compensating the expansion or contraction of connecting means arranged between two relatively fixed points, comprising two weighted pivoted levers each attached by its free extremity to one of the severed ends of said connecting means and normally disconnected from each other and relatively movable independently to main-

tain tension on the respective connecting means, and means adjustable automatically upon the movement of one of said levers to connect the levers and thereby cause them to move in unison should sufficient force be exerted upon said connecting means.

2. Apparatus for compensating the expansion or contraction of connecting means arranged between two relatively fixed points, comprising two pivoted levers each at their free extremity attached to or engaged by one of the severed ends of said connecting means, and a locking device arranged between the levers and adjustable automatically with regard thereto according to the swing of the levers adapted, upon the exertion of sufficient force upon said connecting means, to lock the levers together at, within limits, any position thereof.

3. Apparatus for compensating the expansion or contraction of connecting means arranged between two relatively fixed points, comprising two pivoted levers each at their free extremity attached to or engaged by one of the severed ends of said connecting means, and a link block arranged between the levers movable automatically according to the swing of one of the levers adapted to engage or almost engage both the levers at, within limits, any position of the levers. 20
